UNITED STATES PATENT OFFICE.

FRED WAGNER, OF MIAMI, OKLAHOMA, ASSIGNOR OF ONE-FOURTH TO JOHN RITCHIEY
AND ONE-FOURTH TO CLYDE WAGNER, BOTH OF JOPLIN, MISSOURI.

AIR-FILTER FOR CARBURETERS.

1,209,911.

Specification of Letters Patent. Patented Dec. 26, 1916.

Application filed October 11, 1915. Serial No. 55,252.

To all whom it may concern:

Be it known that I, FRED WAGNER, a citizen of the United States, residing at Miami, in the county of Ottawa and State of Oklahoma, have invented certain new and useful Improvements in Air-Filters for Carbureters, of which the following is a specification, reference being had to the accompanying drawings.

10 This invention comprehends certain new and useful improvements in attachments or accessories for internal combustion engines of motor wheels, motorcycles, automobiles, or the like, and relates particularly to a device for filtering the air before it enters into the carbureter.

15 The invention has for its primary object a durable and very efficient device of this kind which may be readily attached to the air inlet pipe or port of a carbureter, and serve to effectively prevent the dust, which is manifestly so injurious, from entering the carbureter, and thence passing in the gaseous mixture into the engine.

20 25 A further object of the invention is a device of this kind which is composed of comparatively few parts that may be readily manufactured and assembled and very easily detached from each other so that the device may be cleaned of the accumulation of dust and the like from time to time. And the invention also aims to generally improve devices of this kind so as to render them more useful and commercially desirable.

30 35 With these and other objects in view, as will more fully appear as the description proceeds, the invention consists in certain constructions, arrangements and combinations of the parts that I shall hereinafter more fully describe and claim.

40 45 For a full understanding of the invention, reference is to be had to the following description and accompanying drawing, in which-

Figure 1 is a side elevation of an air filter for carbureters embodying the improvements and principles of my invention. Fig. 2 is a longitudinal sectional view 50 through the device. Fig. 3 is an end view thereof, and Fig. 4 is a detail transverse section on the line 4-4 of Fig. 2.

55 Corresponding and like parts are referred to in the following description and designated in all of the views of the accompanying drawing by like reference characters.

My improved air filter for carbureters comprises a preferably cylindrical casing 1, preferably provided at its ends with screw threads 2 and 3, for engagement by the screw caps 60 4 and 5. The screw cap 5, just referred to, like the screw cap 4, and casing 1, is preferably formed of metal, and is provided with a preferably centrally disposed opening in which a tube or collar 6 is secured 65 in any desired way, said collar preferably projecting from both sides of the cap and the forwardly or outwardly projecting portion constituting a nipple whereby the device may be readily attached to the air intake pipe or in the air inlet port of the carbureter, any suitable fittings or reducing portions being used, as required.

Fitting within the casing 1 and preferably disposed centrally therein, is a cylinder 7, the body portion of which is composed 75 of some reticulated or foraminous substance as, for example, wire fabric, as shown, and the ends of which comprise preferably a metallic collar 8 and a cap 9 having a closed 80 bottom, the collar 8 being adapted to fit within the collar 6 hereinbefore referred to, and the cap 9 being designed to abut against the screw cap 4, the body of which, in contradistinction to its rim, is composed of 85 some screen-like material as, for example, wire fabric, as indicated at 10. This screw cap 4 tends to prevent gravel and the like from entering into the annular space between the cylinder 7 and casing 1, as is 90 manifest, while it does not obstruct in any way the in-rush of air, and manifestly, as the central portion of the screw cap 4 abuts against the imperforate bottom of the cap 9, air can only flow in through the surrounding 95 circular portion of the screw cap 4 which is substantially co-extensive with the annular space between the casing and cylinder.

A filtering medium, preferably composed 100 of woolen flannel and designated 11, is adapted to be slipped over the reticulated or foraminous portion of the cylinder 7, this filtering medium being preferably saturated to the desired extent with coal-oil or the like, and thus it will be understood that 105 as the air enters through the screen-like body portion of the screw cap 4 into the annular space 12 between the casing and cylinder, it will flow inwardly into the cylinder 7 through this filtering medium 110 and all of the dust will be excluded and caught by the woolen flannel, leaving only

pure air to flow forwardly through the collars 8 and 6 and thence into the carbureter.

From the foregoing description in connection with the accompanying drawing, the 5 operation of my improved air filter will be apparent. In the practical use of the device, it is attached to the inlet pipe or air inlet port of a carbureter, and manifestly, as the dust-laden air enters into the space 10 12 between the casing 1 and its inclosed cylinder 7, its only outlet will be through the filtering medium 11 which will catch all of the dust and the pure air will pass into the cylinder 7 and thence immediately find 15 its way through the collars 8 and 6 into the carbureter. In order to clean the device, it is only necessary to remove the screw cap 4 and then withdraw the cylinder 7 with its surrounding lining 11 of woolen flannel or 20 the like, and the dust which has accumulated on the latter can be very easily removed. Preferably, I propose to supply one or more extra flannel sleeves of filtering material whereby as, for example, on the 25 road, a used sleeve may be easily taken off and a fresh one applied, without the necessity of cleaning the used sleeve.

While the accompanying drawing illustrates what I believe to be the preferred 30 embodiment of my invention, it is to be un-

derstood that the invention is not limited thereto, but that various changes may be made in the construction, arrangements and proportions of the parts without departing from the scope of the invention as defined 35 by the appended claim.

What is claimed, is:

An air filtering device for carbureters comprising a tubular member having one end open and its opposite end provided with 40 an eduction opening, a reticulated fabric overlying the open end of the member and detachably engaged with the member, a tubular reticulated member detachably supported within the first named member and in communication with the eduction opening, said second named member being of a diameter less than the diameter of the first named member, an imperforate cap insertible within the outer end of the second member for closing the same, and a pervious and absorbent outer covering for the second named member.

In testimony whereof I hereunto affix my signature in the presence of two witnesses.

FRED WAGNER.
